FIG. 1.

FIG. 2.

FIG. 4.

FIG. 3.

FIG. 5.

FIG. 6.

FIG. 7.

FIGURE 1 is a side elevational view of a cabinet knob incorporating our new design;

FIG. 2 is a front elevational view thereof;

FIG. 3 is a front elevational view of an alternate form of cabinet knob wherein the difference from FIGS. 1 and 2 resides in the omission of the back plate;

FIG. 4 is a sectional view taken along a plane corresponding to line 4—4 of FIG. 1;

FIG. 5 is a fragmentary enlarged sectional view taken as indicated by line 5—5 of FIG. 4;

FIG. 6 is a front elevational view similar to FIG. 2 and illustrating another alternate form of cabinet knob; and

FIG. 7 is a front elevation of another alternate form of cabinet knob wherein the difference from FIG. 6 resides in the omission of the back plate.

The characteristic feature of our design resides in the configuration and arrangement of specific decorative details on the front surfaces.

The stippled shading indicates areas of contrasting texture.

We claim:

The ornamental design for a cabinet knob or similar article, substantially as shown and described,
